UNITED STATES PATENT OFFICE

ALANTSER F. LARSEN, OF MANITOWOC, WISCONSIN, ASSIGNOR TO ALUMINUM GOODS
MANUFACTURING COMPANY, OF MANITOWOC, WISCONSIN

DESIGN FOR AN ELECTRIC PERCOLATOR

Application filed January 13, 1932. Serial No. 42,466. Term of patent 3½ years.

To all whom it may concern:

Be it known that I, ALANTSER F. LARSEN, a citizen of the United States, of Manitowoc, in the county of Manitowoc and State of Wisconsin, have invented a new, original, and ornamental Design for an Electric Percolator, of which the following is a specification, reference being had to the accompanying drawing, forming part thereof.

Fig. 1 is a side elevational view of the electric percolator, showing my new design.

Fig. 2 is a top plan view thereof.

I claim:

The ornamental design for an electric percolator, as shown.

In testimony that I claim the foregoing I have hereunto set my hand at Manitowoc, in the county of Manitowoc and State of Wisconsin.

ALANTSER F. LARSEN.
